UNITED STATES PATENT OFFICE.

MARGARET R. CROWE, OF LUCASVILLE, OHIO.

CULINARY IMPLEMENT.

1,164,785.

Specification of Letters Patent. Patented Dec. 21, 1915.

Application filed March 8, 1915. Serial No. 13,000.

To all whom it may concern:

Be it known that I, MARGARET R. CROWE, a citizen of the United States, residing at Lucasville, in the county of Scioto and State 5 of Ohio, have invented certain new and useful Improvements in Culinary Implements, of which the following is a specification, reference being had to the accompanying drawings.

10 My present invention relates to new and useful improvements in culinary implements and has particular reference to a novel form of dough cutter.

15 The primary object of my invention is to provide a simple and efficient cutter which is particularly adapted for use in making noodles.

20 A more specific object is to provide a noodle cutter consisting essentially in a wire handle member, a plurality of disks which are connected to rotate as an entirety when pushed by the handle member over the dough, and a cleaner which is supported by the handle in the proper relation to the cutter disks and is formed from a single length 25 of wire.

25 The above and other incidental objects are accomplished by such means as are illustrated in the accompanying drawings, de- 30 scribed in the following specification, and then more particularly pointed out in the claim which is appended hereto and forms a part of this application.

35 With reference to the drawings, wherein there has been illustrated the preferred embodiment of this invention as it is reduced to practice, and throughout the several views of which similar reference numerals designate corresponding parts, Figure 1 is a side 40 elevation. Fig. 2 is a front elevation; and Fig. 3 is a detail view of the handle.

45 The implement, as embodied in the accompanying drawings, includes broadly, a handle 10, a cutting element 11, and a cleaner 12.

45 The handle 10 is formed from a single length of relatively heavy resilient wire which is bent to produce a substantially rectangular body portion 13. The ends of the wire at the terminal of the body portion are 50 twisted longitudinally about each other to form the stem or shank 14. Beyond the end of this shank the two portions of wire are bent at right angles and then outwardly, as at 15 and are then bent as at 16 and 17, to

produce the parallel arms which, in connection with the members 15, constitute a substantially U-shaped frame, in which the cutting element 11 is rigidly supported. 55

The cutting element heretofore designated as an entirety by the numeral 11, consists of 60 an axle 18, on which are mounted a plurality of circular cutters 19. These cutter disks 19 are held in parallel spaced relation to each other by means of spacer disks or washers 20. The members 19 and 20 are bound together 65 so that they will rotate as a unit on the axle 18 by means of a pair of nuts 21. These nuts 21 are threaded on the terminals of the axle and are disposed to bear against the inner portions of the arms 16 and 17. 70 The terminals of the axle are journaled in the eyelets 22 formed on the terminals of the arms 16 and 17.

75 The cleaner bar is, as previously stated, formed from a single length of wire. This wire is bent at a number of intermediate points to produce the substantially U-shaped fingers 23. The terminals of the wire are bent to extend laterally as at 24 to provide means whereby the cleaner bar can be attached to the side arms 16 and 17 of the cutting holding frame. One of the U-shaped finger members 23 is disposed between each pair of cutter disks. The arms of each cleaning finger are spaced such a distance 80 that they will merely clear the cutter disks whereby any material which may adhere to the disks will be engaged and dislodged. 85

90 In reduction to practice, it has been found that the form of this invention illustrated in the drawings, and referred to in the above description as the preferred embodiment, is the most efficient and practical; yet realizing that the conditions concurrent with the adoption of this device will necessarily vary, 95 it is desirable to emphasize the fact that I reserve to myself the right to make various minor changes in the details of construction, proportion and arrangements of the different parts, without sacrificing any of the advantages of the invention or the principles thereof, as defined in the appended claim. 100

What is claimed is:—

105 A device of the character described including a handle, a cutter rotatably mounted therein, said cutter including an axle, and a plurality of cutter disks mounted thereon in parallel spaced relation to each other, and

a cleaner member carried by the handle, said cleaner member being formed from a single length of wire bent at a plurality of intermediate points to produce a plurality of spaced substantially U-shaped cleaning fingers, there being a cleaning finger interposed between each pair of cutter disks.

Copies of this patent may be obtained for five cents each, by addressing the "Commissioner of Patents, Washington, D. C."

In testimony whereof I hereunto affix my signature in the presence of two witnesses.

MARGARET R. CROWE.
